G. J. LEUVELINK

EXPANDABLE STOPPER

Filed Jan. 11, 1921

UNITED STATES PATENT OFFICE.

GERRIT J. LEUVELINK, OF PATERSON, NEW JERSEY.

EXPANDABLE STOPPER.

Application filed January 11, 1921. Serial No. 436,567.

To all whom it may concern:

Be it known that I, GERRIT J. LEUVELINK, a citizen of the United States, residing at Paterson, in the county of Passaic and State 5 of New Jersey, have invented new and useful Improvements in Expandable Stoppers, of which the following is a specification.

My present invention has reference to a means for plugging boiler tubes to permit 10 of repairs being made thereto.

My object is to produce a simple, comparatively cheap and thoroughly efficient means which may be readily inserted in a boiler tube, and adjusted to effectively plug the 15 tube.

A further object is the production of a plug or stopper for either water or fire tubes of boilers which comprises a plurality of parts that are inserted as a unit in the 20 tube and adjusted to expand the same against the tube to stop or plug the tube, and also in which the nut element employed in the adjustment may be embedded in a fire clay or the like to prevent the effect of the 25 heat thereon, and also to insure the ready removal thereof from the bolt with which it engages.

The foregoing, and other objects which will appear as the nature of the invention 30 is better understood, may be accomplished by a construction, combination and operative arrangement of parts, such as is disclosed by the drawings which accompany and which form part of this application.

35 In the drawings:—

Figure 1 is an approximately central vertical longitudinal sectional view through the improvement showing the same employed for stopping or plugging a boiler tube.

40 Figure 2 is a sectional view approximately on the line 2—2 of Figure 1.

Figure 3 is an end view of the wedges.

Figure 4 is a similar view of the inner clamping ring.

45 Figure 5 is a similar view of the outer clamping ring.

Referring now to the drawings in detail, the numeral 1 designates a boiler plate and 2 a boiler tube which has its bore plugged or 50 stopped in accordance with this invention. The improvement includes four segmental wedges, 3 respectively. Each of the wedges has its outer face rounded to correspond with the inner contour of the tube 2 and its 55 inner face provided with a straight face 4 that flares inwardly from its outer to its in-

ner end, that is from the end which is arranged next to the boiler plate 1. All of the wedge segments 3 have peripheral depressions 5 designed to register, and received in these depressions is a split spring member 6 that holds the wedge sections assembled.

Before the wedge members 3 are inserted in the tube 2, there is arranged in the flared bore provided by the assembled wedge segments, the flared head 6 of a bolt member 7. The head 6 presents four angle surfaces each of which engages with one of the flared inner walls 4 of the respective wedge segments 3.

Arranged on the bolt 7 for contacting engagement with the inner face of the wedge, is a clamping ring 8. The ring 8 has its outer face provided with an annular groove 9 positioned to receive therein an annular flange that forms a tongue 10 on the confronting face of the second clamping ring 11. The face of the clamping ring 11, on which the tongue 10 is formed, is flared outwardly, as at 12, to the periphery of the ring, and from the opposite face of the said ring, the said face is flared inwardly, as at 13 to the bore of the ring. These flared surfaces, in connection with the straight confronting face of the ring 8 provide pockets for compressible gaskets 14 and 15 respectively. The ring 11 has its opposite or outer face provided with a depression forming a pocket 16. Screwed on the bolt 7, and designed to contact with the inner wall provided by the pocket 16 in the ring member 11, is a nut 17. The pocket is of a sufficient area to permit of the free insertion of a wrench for turning the nut. The nut turned on the bolt will draw the bolt longitudinally in an outward direction through the tube 2, thus spreading the segmental clamping members 3 to bring the latter in tight engagement with the bore of the tube. A further turning of the nut on the bolt will force the ring 11 toward the ring 8, causing the tongue 10 of the ring 11 to enter the groove 9 of the ring 8, and also compressing the gaskets 14 and 15 between the confronting faces of the ring, thus insuring a water tight joint between the bolt and the rings as well as between the rings and the tube. The pocket 16 serves as a receptacle for a fire clay or similar packing 18 that surrounds the outer end of the bolt and the nut, thus protecting these members from excessive

heat, and permitting the ready separation of the nut from the bolt when the fire clay has been removed.

It is thought that the foregoing description, when taken in connection with the drawings will fully set forth the construction and advantages of the improvement to those skilled in the art to which such inventions relate without further detailed description.

Having described the invention, I claim:—

In a plug or stopper for boiler tubes, a wedge made up of a plurality of independent non-contacting segments each having its inner face flared and its outer peripheral face grooved, a split ring in the groove for holding the sections assembled, opposed rings at the outer face of the wedge, the inner ring having its outer face provided with a continuous groove, the outer ring having its inner face provided with a

continuous tongue to be received in the groove, the said inner face of the outer ring being flared from the tongue to its bore and to its periphery, compressible gaskets between the rings at the said flared portion of the outer ring, said outer ring having its outer face dished to provide a pocket, a bolt having wedge faces on one end thereof engaging the flared sections, a nut screwed on the bolt and received in the pocket of the outer ring and designed to move the bolt longitudinally to cause the head thereof to expand the wedge sections and to move the outer ring toward the inner ring to compress the gaskets therebetween, and said pocket designed to receive a heat protecting element for the end of the bolt and the nut.

In testimony whereof I affix my signature.

GERRIT J. LEUVELINK.
